UNITED STATES PATENT OFFICE.

MICHAEL PARIDON, OF BARBERTON, OHIO, ASSIGNOR OF ONE-HALF TO HENRY A. RUDD, OF BARBERTON, OHIO.

HEAD FOR PNEUMATIC TIRES.

1,200,015.

Specification of Letters Patent.

Patented Oct. 3, 1916.

Application filed June 19, 1916. Serial No. 104,561.

To all whom it may concern:

Be it known that I, MICHAEL PARIDON, a citizen of the United States, residing at Barberton, in the county of Summit and State of Ohio, have invented new and useful Improvements in Beads for Pneumatic Tires, of which the following is a specification.

This invention relates to improvements in beads used in pneumatic-tire-shoes and the object of the invention is to provide a bead for a pneumatic-tire-shoe, the strength-giving properties of the latter residing largely in one or more layers composed of a flexible member, such for instance, as a cord.

More specifically the invention resides in a strengthening core incorporated in the bead for holding the cord at the sides of the tire-shoe and which is especially useful in the construction of a tire-shoe wherein the shoe is strengthened by a single cord wrapped helically about two cores spaced apart with the two portions of each complete convolution arranged at approximately 25 right angles to each other and oblique to the longitudinal line of the shoe, or in other words where the strength-giving properties of a tire-shoe reside in a single cord, for instance, carried from one bead-core obliquely to and around the other bead-core to thereby form a portion of one layer of the shoe fabric and which is carried from thence across the tread to the first bead core, and at right angles with respect to the first portion 35 of the cord, and obliquely disposed with respect to the longitudinal line of the tire-shoe to form a portion of the second layer.

My invention, therefore, primarily resides in the construction of the reinforcing element which is placed in each bead and by which the folded or looped portions of the cord, at the sides of the tire-shoe, may be securely and accurately anchored to hold each convolution of the cord in proper position and in spaced relation with respect to the other convolutions so that all of the convolutions will be held against transverse movement or slipping on the bead core. The anchor being so constructed that an approximately perfect seat is provided for each looped portion.

With the foregoing and other objects in view, the invention consists in the novel construction, combination and arrangement of parts constituting the invention to be here-

inafter specifically described and illustrated in the accompanying drawings which form a part hereof wherein is shown the preferred embodiment of the invention, but it is to be understood that changes, variations and modifications can be resorted to which come within the scope of the matter hereinafter claimed.

In the drawings in which similar reference numerals indicate like parts in the different figures, Figure 1, is a transverse sectional view of a tire-shoe embodying this invention, and Fig. 2, is an enlarged detail of the reinforcement or anchor employed with a few convolutions of a cord fabric in operative engagement therewith.

In the drawings reference numeral 1 denotes an ordinary tire-shoe provided with the usual beads 2. The strength-giving properties of the shoe are furnished by one or more layers of a flexible member, such for instance, as a cord. The construction of both beads is identical and hence a description of one is believed to be sufficient for both. Positioned in each of the beads is an inelastic, non-extensible, annularly-fashioned member 3, the outer face of which is provided with a helical groove 4 in the general form of a V-thread and between the grooves 4 are the usual helical ribs 5. Each reinforcing member 3 may be in the form of an annulus or endless ring or may be in the form of a broken ring with ends thereof united, and in constructing the shoe these are incorporated in the beads as they are ultimately formed. The tire-shoe fabric is preferably constructed from a single strength-giving cord carried from one bead core to the other bead core and from the second bead core to the first bead core, but with the second portion at right angles with respect to the first portion so that the second portion is superposed on the first portion and at right angles thereto and with both portions oblique to the longitudinal line of the tire-shoe.

It is contemplated in this invention that the cord which forms the strength-giving properties of the shoe will be wound singly about two equally spaced reinforcing members or cores 3 while held in spaced relation and the winding carried out until two complete layers of strength-giving material are formed for embodiment in a tire-shoe. It is further contemplated that the cord which forms the strength-giving element for the

tire-shoe will be a substantially continuous cord and to illustrate the arrangement of the cord with respect to the reinforcing members 3 it may be assumed that the cord 5 denominated by the reference numeral 4' is carried from the opposite bead core over the tread of the tire and to, seated in, and pass partially around one of the convolutions of the groove 4 and from thence carried outwardly and to become cord 5'. This cord will be carried completely around the circumference of the two spaced cores and after a complete revolution about them the cord will then be in the position shown by 5 the numeral 6 and pass partially around the reinforcing element 3 and become cord 7 in the second layer. The portions of the cords denominated by the reference numerals 4' and 6 will form the inner layer of 20 the strength-giving fabric of the tire and the layers formed by the cords 5' and 7 form the second or outer layer of the fabric and it will be noted that they cross the layers 4' and 6 at right angles and that 25 both are oblique to the longitudinal line of the reinforcing member 3. The pitch, inclination, size, configuration or general conformation of the groove 4 in each reinforcing element may be changed or altered to 30 accommodate it to receive the various convolutions of the cord from which the tire-shoe fabric is formed and the spiral rib 5 may be round or sharp as desired. By utilizing the reinforcing element 3 provided 35 with a helical groove 4 each successive convolution of cord can be carried over the tread and seated in one of the convolutions of the groove 4 and thence carried outwardly over the tread at right angles with respect to 40 the first portion of the convolution. The various convolutions of the groove 4 forming efficient seats and spacing members for holding the looped portions of each convolution of the core accurately in position and the 45 reinforcing member 3 provides a secure and non-yielding anchor for holding the cords

from being shifted from their respective positions.

I claim,

1. A pneumatic-tire-shoe provided in each 50 bead with a circumferentially-extending annularly-fashioned member, the exterior of each of which is provided with a helical groove constituting a seat to receive the looped portions of a strength-giving cord 55 extending from side to side of the tire-shoe.

2. A pneumatic-tire-shoe provided in each bead with a circumferentially-extending annularly-fashioned reinforcing member, the outer face of which is provided with a 60 spiral groove constituting a combined seat and spacing medium for a strength-giving cord extending from side to side of the tire-shoe and across the tread thereof to hold the successive convolutions of said cord in 65 spaced relation.

3. A reinforcement for a pneumatic-tire-shoe bead comprising an annularly-fashioned inextensible member provided with a helical or spiral groove in the outer 70 face thereof.

4. A reinforcement for a pneumatic-tire-shoe bead comprising an annularly-fashioned member extending circumferentially of said bead and having a spiral 75 groove in the outer face thereof.

5. A reinforcing member for pneumatic-tire-shoe beads comprising a ring-like member having the exterior thereof provided with a helically-disposed channel. 80

6. A reinforcing member for pneumatic-tire-shoe beads comprising a ring-like member of inextensible material the outer face of which is provided with a spirally-arranged groove of sufficient depth to constitute a seat for a cord-like member incorporated as a strength-giving element in said tire-shoe. 85

In testimony whereof I have hereunto set my hand.

MICHAEL PARIDON.
